GUIDE FOR RUNNING FLEXIBLE MATERIAL

Jack B. Lyle, Paterson, N. J.

Application December 21, 1944, Serial No. 569,254

15 Claims. (Cl. 242—157)

1

This invention relates to means for guiding flexible material, for instance—cordage, wire and cable, and is particularly useful when the material is required to change its course of direction when running, or must have a guide to hold it in its course. In its preferred form it consists of a number of rings, preferably flat-sided, substantially cylindrical on the outer side, and on the inner side reversely curved, somewhat like a wedding ring reversed or turned outside in. These rings, when made of extremely hard material, last in use a very long time. I have found that what is known in the trade as "Cemented carbide," which possesses high wear-resisting properties, is a satisfactory material for rings.

The rings may be mounted or held in some suitable opening, preferably round in cross-section, and if they are to guide the material in a curve, curved at the desired angle, which, by the way, requires much less space for the guiding device as a whole than when a sheave is employed.

In the drawing accompanying and forming part of this specification wherein one practicable form of my invention is illustrated; the accompanying drawings comprise the following:

Fig. 1 is a view in longitudinal section of a part of a stranding machine employing my invention in several forms.

Fig. 2 is an enlarged view of the guide illustrated at the left hand end of Fig. 1. In this view the guide is of a size which is frequently employed in practice on materials such as steel and non-ferrous wires and strands.

Fig. 3 is a similar view of the guide shown at the lower left hand end of Fig. 1, and

Fig. 4 shows one of the preferred forms of ring very much enlarged.

For a better understanding of the invention reference is made to a machine in which it has been used. A part of one of such machines is illustrated in Fig. 1, and shows several forms of this invention, Fig. 1 showing the cross-section of a stranding machine rotor, the body proper 10 of which is caused to revolve by means of a V pulley 11 forming part of the body. Within this part of the revolving structure are shown two cradles 13 and 14, which stand practically still while the casing revolves. The material being treated 15, coming from the cradle 13, passes through one of the improved guides 16, which stands still with the cradle, its supporting housing 17 revolving with the part 10 to which it is fastened; it then goes to other of my guides 18, 19 and 20, all fast with part 10, to the point 21, where it and strands of material 22 and 23,

2

coming from another part of the machine and from the cradle 14, meet and are twisted together. The material 23, going from cradle 14, passes through a guide 24, similar to the guide 16 of cradle 13, but goes directly to the point 21 of twisting. The material 22 coming from the rear of the machine passes through the guide 25, illustrated in Fig. 2, thence to the shell of the machine to the guide 26, illustrated in Fig. 3, along the shell to the guide 27, thence in an oblique direction to the guide 28 and to the meeting and twisting point 21.

It may now be in order to describe some of the forms of guide used in this illustrative form of machine. That shown in detail in Fig. 2, and seen at the left hand end of Fig. 1, is represented by the character 25 and comprises a piece of, we will say, metal 30 having a hole 31 through it in the direction of movement of the material being treated and flaring as at 32. The hole is preferably round in cross-section and develops into the enlargement 32, which is preferably much larger at its outer part 33 than the bending tube. This tube comprises a number of very hard rings 34, formed of high wear-resisting material, each ring having flat opposite sides 35, 35, a cylindrical outer surface 36, and a rounded or convex inner surface 37, see Fig. 4. Part of the tube, the collection of rings 34 and their enclosing casing of coiled wire 38 are positioned within the guide 30. The other end, toward the right in the illustration, is free for adjustment itself to the angle required of it in the reach to the guide 26 at the outer part of the casing 10. It will be noted here that for a sheave giving the same radius of bend as this device, the space required in the plane of bending would be increased many times. The form of the guide 26 is shown at the bottom of Fig. 1 (strictly, it will not be the bottom since 10 rotates), near its left hand end, and illustrated enlarged in Fig. 3.

One form of the ring 34 is shown in Fig. 4 very much enlarged. In Fig. 3 there is a bent tube 40 encasing an assembly of rings 34 carried in a flexible member 38, which may be made of metal or composition. At the entering end of the flexible member 38 a ring 41 is applied to the flexible member 38. Outwardly of the ring 41, electrical welding 42 or the like, may be applied, as well as the smaller ring 43, and at the opposite or exit end of the spring coil 38 is provided an end convolution 38a, of smaller diameter than the remainder of said spring coil to hold said series of rings 34 properly in place within said spring coil 38. The right hand end of the tube

40 is seen resting on the casing 10, and at the other end held at the proper angle to incoming material 22 by a block 44 held in place by some suitable means for instance electrical welding 45.

What I claim as my invention and desire to secure by Letters Patent is:

1. A device of the character described comprising an enclosure, a series of annular members of high wear-resisting material disposed within said enclosure, and means interposed between said enclosure and said series of annular members for retaining said annular members in assembled relation.

2. A device of the character described comprising a guide having a curved passage extending therethrough, a resilient tubular member in said curved passage, and a series of annular members of high wear-resisting material arranged side-by-side and flexibly retained in assembled relation within said resilient tubular member.

3. A device of the character described comprising a tubular enclosure, a series of individual annular members of high wear-resisting material arranged in said enclosure in side-by-side relation, and resilient means disposed in said enclosure and surrounding said annular members for maintaining said series of annular members in assembled relation.

4. A device of the character described comprising a tubular enclosure, a series of individual annular members of high wear-resisting material each member having a flat outer surface and a curved inner surface, said members being disposed in said enclosure in side-by-side relation and forming a continuous lining, a coil spiral surrounding said annular members for maintaining the same flexibly in assembled relation; said coil spiral being interposed between the outer sides of said series of annular members and the inner wall of said tubular enclosure.

5. A device of the character described comprising a tubular enclosure, a series of individual annular members of high wear-resisting material disposed in said enclosure in side-by-side relation; said annular members having transversely rounded inner surfaces, and a coil spring surrounding said annular members for maintaining the same flexibly in assembled relation.

6. A device of the character described comprising a tubular enclosure, a series of individual annular members of high wear-resisting material disposed in said enclosure in side-by-side relation; said annular members having transversely rounded inner surfaces; a coil spring surrounding said annular members for maintaining the same flexibly in assembled relation, and means at the opposite ends of said enclosure for securing said annular members against longitudinal movement within said coil spring.

7. A device of the character described comprising a tubular enclosure, a plurality of annular members composed of cemented carbide disposed in side-by-side relation in said enclosure, and resilient means disposed about said annular members for holding the same flexibly in assembled relation.

8. A device of the character described comprising a tubular enclosure, a plurality of annular members of cemented carbide disposed in said

65 enclosure, and a spring coil surrounding said annular members for holding the same in assembled relation.

9. A device of the character described comprising a longitudinally curved tubular enclosure, a plurality of annular members of cemented carbide disposed in said enclosure, and a spring coil surrounding said annular members for holding the same flexibly in assembled relation.

10. A device of the character described comprising a series of annular members of high wear-resisting material arranged in side-by-side relation, said annular members having flat outer surfaces, and a flexible, resilient tubular member surrounding said series of annular members for maintaining the same flexibly in assembled relation.

11. A device of the character described comprising a series of annular members of high wear-resisting material arranged in side-by-side relation, said annular members having flat outer surfaces, and a closely-wound spring coil surrounding said series of annular members for maintaining the same flexibly in assembled relation.

12. A device of the character described comprising a series of annular members of high wear-resisting material arranged in side-by-side relation, said annular members having flat outer surfaces, a closely-wound spring coil surrounding said series of annular members for maintaining the same flexibly in assembled relation, and means secured to the opposite ends of said spring coil for retaining said annular members within said spring coil.

13. A device of the character described comprising a series of annular members of cemented carbide arranged in side-by-side relation, said annular members having flat outer surfaces, a closely-wound spring coil surrounding said series of annular members for maintaining the same flexibly in assembled relation, and means secured to the opposite ends of said spring coil for retaining said annular members against longitudinal displacement within said spring coil.

14. A guide for a running flexible material, comprising a hollow body, a plurality of rings of hard material disposed interiorly of said hollow body, each ring having a flat outer surface and a curved inner surface, and resilient means embracing said rings at their said flat surfaces and arranged to hold said rings to one another while permitting the bending of their assembly.

15. A guide as defined by claim 14 in which the radius of curvature of the curved inner surface of said ring conforms to the radius of curvature of the path of travel of the flexible material.
